UNITED STATES PATENT OFFICE.

ERNEST A. WULLENWEBER, OF DETROIT, MICHIGAN, ASSIGNEE TO MORGAN &
WRIGHT, A CORPORATION OF MICHIGAN.

BEST AVAILABLE COPY METHOD AND APPARATUS FOR TREATING RUBBER.

1,337,536.

Specification of Letters Patent. Patented Apr. 20, 1920.

Application filed October 5, 1917. Serial No. 194,833.

To all whom it may concern:

Be it known that I, ERNEST A. WULLENWEBER, a citizen of the United States, residing in Detroit, county of Wayne, and State of Michigan, have invented certain new and useful Improvements in Methods and Apparatus for Treating Rubber, of which the following is a full, clear, and exact description.

10 My invention relates to a method and apparatus for treating rubber and more particularly to a method, and an apparatus, by which the rubber is subjected to humid air or other gas having a temperature and a 15 percentage of saturation suitable for removing the moisture-content of the rubber without causing oxidation of the surface of the rubber being treated.

It is well known in this art, that raw 20 rubber, as well as rubber composition, whether the same has been previously dried or not, are benefited as to quality, by being subjected to humid air maintained at a temperature materially below the vulcanizing 25 temperature. It has been found difficult however to secure uniformity in the quality of the rubber thus treated, by reason of a constant variance or fluctuation both in the 30 temperature of the humid air and in the degree of saturation thereof.

By my present invention, I am enabled 35 not only to maintain the humid gas in a room or chamber containing the rubber to be treated, at a substantially uniform temperature at all times, but to secure and maintain a substantially constant degree of saturation of this gas. Furthermore the manner 40 of conditioning the gas is such as to prevent the development of a temperature in the room or chamber containing the rubber, in excess of a predetermined temperature, that portion of the gas, the temperature of which drops materially below said predetermined 45 temperature and which becomes supersaturated or fouled, being withdrawn from said room or chamber and replaced by fresh gas of the desired temperature and humidity. Under normal conditions I constantly circulate a portion of the humid gas in a closed 50 circuit including said room or chamber so long as the gas in the room is at the required temperature and degree of saturation, this circuit being interrupted during the withdrawal of the gas having a lower temperature and higher degree of saturation and 55 its replacement by a fresh supply of gas at

the required temperature and saturation. In this manner, the gas in the room stratifies by convection, the more rarefied and less humid air being withdrawn from adjacent to the top of the room, and the cooler and supersaturated or fouled gas being withdrawn from the lower part of the room.

In an apparatus used in the practice of my method, I not only provide means for 60 supplying vapor in the desired predetermined quantity to the gas, and means for heating the saturated gas and circulating it within the room or chamber, but means controlled by appliances sensitive to changes of 65 temperature and of humidity arranged in the room or chamber itself, whereby the circulation of the humid gas, the withdrawal of the supersaturated or foul gas, and the admission of fresh gas to replace same, are 70 automatically controlled by conditions within 75 said room or chamber and about the rubber being treated.

The circulation and purging means are so 80 constructed and arranged as to insure a substantially uniform distribution of the humidified gas throughout the room or chamber, and the withdrawal of the foul or supersaturated gas from different portions of the room or chamber in a manner to insure substantially uniform conditions throughout 85 said room or chamber. Furthermore the thermostat within the room or chamber is so connected with the means for humidifying the gas when conditioning it for delivery 90 to the room or chamber as to control the temperature of said gas and prevent the development of a temperature in excess of that required to properly treat the rubber.

The invention consists in a method and 95 in an apparatus for the practice of said method containing the novel features of construction and combination of parts, all as hereinafter set forth and described and more particularly pointed out in the claims here- 100 to appended.

Referring to the drawings,

Figure 1 is a plan view showing diagrammatically an apparatus used in the practice 105 of my method;

Fig. 2 is a vertical section on the line 2—2 of Fig. 1; and

Fig. 3 is a vertical section on the line 3—3 of Fig. 1.

Like reference numerals refer to like parts throughout the several views.

In the practice of the invention, rubber

or like material to be treated is arranged on poles or in trays within a closed room or chamber, into which is discharged fresh air, carbon dioxid, nitrogen or other suitable gases at the desired temperature and more or less humid. The air or gas is drawn through a suitable heater and forced into the chamber, where it stratifies in a manner to gradually cause that portion of the gas which becomes cool and supersaturated, to descend in the room and that portion of the gas which becomes less saturated and is of a higher temperature, to ascend. This stratification, however, varies with the rate of flow or movement of the gas, and when the rate of movement is relatively rapid, it is inconsiderable if not negligible. The rubber or other material is preferably supported at a point intermediate the ceiling and floor of the room so as to be surrounded by humidified gas having the proper temperature and degree of saturation.

By having the gas flow into the room through a plurality of openings spaced apart vertically or horizontally the inflowing gas is properly distributed throughout the room thus insuring substantial uniformity in the temperature and humidity of the gases throughout the entire room except as to the stratification above referred to.

When the temperature and humidity of the gas within the room, are suitable for conditioning the rubber, I draw a portion of the gas from the upper part of the room, inject steam thereinto, reheat them and return them to the room, thus maintaining a closed circuit of circulating gas in a manner to maintain the intermediate strata thereof in the room at the proper temperature and humidity.

There will, however, be a gradual accumulation of supersaturated gas in the lower part of the room, which gas from time to time is withdrawn, the closed circuit above referred to being interrupted while said gas is being withdrawn, and a fresh supply of heated gas is being delivered into the room to replace the gas thus withdrawn.

An essential characteristic of the method of my invention resides in injecting steam into the gas while being circulated and thereafter passing the gas and steam through a heater to secure a more perfect saturation of said gas and bring it to the desired temperature. In delivering the humidified gas to said room or chamber, and in maintaining the closed circulation of such gas to and from said chamber, I preferably use a force-feed such as a blower, which will draw the gas and steam through the heater and force it into said room or chamber.

I also vary the temperature of the gas being delivered to said room or chamber

in accord with the temperature conditions within the room or chamber, in order to avoid likelihood of the development of excessively high or excessively low temperatures in said room or chamber. This variance in the temperature of the inflowing gas is entirely independent of the conditions governing the withdrawal of the gas from the lower portion of said room or chamber which withdrawal is determined by the degree of humidity of the gas within said room or chamber. I also vary the volume of steam injected into the gas to cause a saturation thereof in accord with the percentage of saturation of the gas contained in said room or chamber.

The method above described not only enables me to provide for the desired degree of saturation of the gas but, by a proper variance in the volume of the steam mixed with the gas and of the temperature to which the steam and gas mixture is subjected before being delivered to said room or chamber, to maintain a substantially uniform temperature and degree of humidity throughout the entire chamber in a manner to insure substantial uniformity in the quality of the rubber or other material treated. Furthermore by reason of my ability to control the temperature and the degree of humidity of the gas within the room, succeeding lots of rubber or other material may be treated under substantially uniform conditions.

The degree of saturation of the gas may range from 20° to 80°, it apparently being merely necessary that the moisture in the gas be sufficiently high to form and maintain a film upon the surface of the rubber being treated and thus prevent the oxidation of this surface or its hardening in a manner to interfere with the displacement of the moisture-content and the proper heating of the entire mass of the rubber. The temperature at which the gas is maintained may also vary according to the condition of the stock being treated, and the manner of supporting same. A more rapid elimination of the moisture-content in the stock may be effected by the use of higher temperatures and for this reason it is desirable to support the stock upon trays rather than upon poles. I have found in actual practice however, that the stock may be properly conditioned upon poles with a temperature ranging from 90 to 115° and that a temperature of as high as 150° may be effectively used when the stock is held upon trays. The only factor in conditioning the stock by this variance in temperature, seems to reside in the time element, as the finished product apparently possesses the same characteristics irrespective of the temperature.

Saturated air may be advantageously used and if the proper degree of humidity be

maintained there seems to be little or no tendency toward the oxidation of the surface of the stock. It is apparent however, that likelihood of such oxidation may be entirely eliminated by the use of an inert gas such as carbon dioxid or nitrogen.

While I have referred above to a varying of the amount of steam injected into the gas being delivered into the room or chamber to accord with the humidity within said room or chamber and the varying of the temperature of this saturated gas to accord with the temperature within the room or chamber, it is apparent that the temperature and the humidity of the room are so related as to make these variances more or less interdependent.

The apparatus used in the practice of the method of my invention comprises a closed room 10 adapted to have rubber or other material supported therein upon poles, trays or in any other desired manner. I have found in practice that it is possible to use a higher temperature in treating rubber stored upon trays than is possible when treating rubber supported by poles inasmuch as the higher temperature has a tendency to soften the rubber and cause it to drop from the pole. When using a higher temperature the rubber or other material may be treated in a shorter time than with a lower temperature, the duration of the treatment however, apparently having no material effect upon the quality of the product. A duct 11, provided with a plurality of branches 12 each having openings 13 and 14 discharging respectively into the upper and lower portions of the room and openings 15 intermediate the openings 13 and 14, is used to deliver humidified gas to said room or chamber in a manner to cause the gas to be substantially equally distributed through all parts of the room or chamber 10. The number of openings 13, 14 and 15, the capacity thereof and of the duct 11 and the arrangement of this duct with relation to said room or chamber may vary indefinitely to accord with the conditions and the capacity of the room or chamber.

I also arrange adjacent the top or ceiling of the room or chamber 10, an off-take duct 16 having a plurality of branches 17 each having an opening 18, 19 and 20 respectively arranged similarly to the openings 13, 14 and 15, so as to provide communication between said duct 16 and all parts of the room or chamber 10. The duct 11 communicates with the discharge port of a blower 21 of any desired construction, the intake of said blower being in communication, through a heater 22 with the discharge end of the duct 16. Leading from said duct 16 and communicating with the atmosphere or any other desired source of gas supply is a branch duct 23.

Arranged in the room or chamber 10 is a purge, or foul gas duct 24 having a plurality of downwardly extending branches 25 opening into the said room or chamber on different levels. The duct 24 opens outwardly of the room or chamber 10 in a manner to cause the pressure within said room to result in a flow of the fouled or super-saturated gas by a natural draft from the room or chamber, although other means for causing this flow of the said gas may be utilized if desired.

Discharging into the inlet of the heater 22 is a steam nozzle 26 for injecting steam into the gas as it passes to said heater. By regulating the volume of the steam the degree of saturation of the gas may be readily controlled and by having the regulating means positioned within the room or chamber the degree of saturation will be determined by conditions about the rubber being treated.

Each of the ducts 16 and 24, and the branch duct 23 is provided with a suitable valve mechanism for controlling the flow of gas therethrough, said mechanism comprising butterfly valves 27 and 28 adjacent the outlets of the ducts 16 and 24 respectively, and a similar valve 29 adjacent the inlet of the branch duct 23. Each of the valves 27, 28 and 29 is adapted to be automatically and synchronously actuated in any desired manner, the valve 27 being opened when the valves 28 and 29 are closed and vice versa.

The steam nozzle 26 is supplied from a pipe 30 having in its length a regulating valve 31 adapted to be opened and closed through the same agency as the valve 29.

The actuation of the valves 27, 28, 29 and 31 is controlled by a suitable hygrometer 32 positioned about midway of the height of the room or chamber 10. In the form of the invention shown, I use a compressor 33 adapted to deliver air under compression to the tank 34. Leading from said tank is an air line 35 communicating with a distributor 36 adjacent the hygrometer 32 and communicating with a pipe line, one branch 37 of which is connected with a suitable diaphragm regulator 38 operatively connected with the valve 28, and other branches 39, 40 and 41 of which are in connection with similar regulators 42, 43, and 44 operatively connected respectively with the valves 31, 27 and 29. Adjacent the distributor 36 is a three way valve 45 operatively connected with said hygrometer, said valve being adapted to permit compressed air to flow to the several diaphragm regulators and to relieve the pressure therein according to the conditions determined by the hygrometer.

Adjacent the distributor 36 is a thermostat 46 controlling a three way valve 47 in a pipe line 48 leading from the distributor 36.

36 and communicating with a diaphragm regulator 49 controlling the steam supply for the heater 22, thus controlling the heating of the saturated gas to a temperature 5 determined by the temperature about the rubber being treated.

At 50 I have indicated a pole for supporting the rubber and at 51 cars containing reticulated trays for the same purpose. 10 The manner of supporting the rubber however, is immaterial to my present invention the purpose of which is to maintain a substantially uniform temperature and humidity of the gas, and control the humidity of 15 the gas delivered to said room or chamber.

The operation of the herein described apparatus is substantially as follows:

Green or rewashed rubber stock having been positioned in the room or chamber 10 20 thereby raising the humidity to the neighborhood of 80%, the hygrometer 32 functions to cause valves 28 and 29 to open and valve 27 to close. Operation of the blower 21 then draws gas through the duct 23 and 25 heater 22 and then forces it through the duct 11 into the chamber. The temperature in the room 10, when the operation is started, is sufficiently low to cause the thermostat 46 to admit air to the pipe line 48 which 30 opens the valve 49 and brings the heater 22 to its maximum temperature. Air is admitted from the duct 11 into a room 10 through a series of openings 13, 14 and 15 into all parts thereof. Because of the high 35 initial humidity of the atmosphere within the chamber 10, the freshly supplied air becomes humidified almost at once to a degree above that to which the hygrometer is preferably set for rapid drying—which has been 40 satisfactorily practised at 30%—consequently it is forced or vented from the room or chamber 10 through the duct 24 and relief damper 28 which is at this time open. Fresh air is continually supplied and ex- 45 hausted from the chamber in this manner until the atmosphere therewithin reaches a humidity below that to which the hygrometer 50 is set when the hairs of the hygrometer contract and admit air under slight pressure to the piping 37-39 and thereby close the valves 28 and 29 and simultaneously open the valve 27 in the return duct 16. This induces a closed system of operation in which a segregated volume of air is end- 55 lessly circulated through the room 10, heater 22 and ducts 16 and 11 which form the closed system. At the beginning of this closed system of operation, the humidity is slightly below the critical degree of humid- 60 ity—as before mentioned, preferably in the neighborhood of 30%—and the temperature is likewise below what we may term the critical temperature at which the thermo- 65 stat functions. The heater 22 is conse- quently at its maximum heating capacity

and the endlessly circulating air being expanded thereby has its relative humidity lowered. The hairs of the hygrometer 32 consequently contract still further and admit air under a greater pressure to the pipe 70 line 39, thereby opening the valve 31 and admitting same through the injector 26 into the circulating volume of air. This of course rapidly raises the humidity of the air being circulated to a point above the critical 75 humidity and interrupts the closed system of operation, the valve 27 being closed and the valves 29 and 28 being opened, steam being cut off from the injector 26 at the same time. The room or chamber 10 is consequently purged of the overly humid gas which is displaced by a quantity of fresh gas drawn through the heater 22 and forced into the chamber by the blower 21.

The cycle of operation above referred to 85 is repeated as determined by constantly varying conditions within the room or chamber 10. The range in the degree of temperature and of humidity of the gas usable in treating the rubber permits the effective 90 utilization of an apparatus as herein described, and while with such an apparatus, the temperature and humidity will be subject to constant fluctuation these fluctuations will always approximate the maximum 95 working degree of both temperature and humidity to which the thermostat and hygrometer are adjusted, within the before mentioned limits.

By the practice of the method and the 100 use of the apparatus of my invention, I am enabled to charge a room or chamber containing rubber to be treated with gas at the proper temperature; to repeatedly circulate gas so segregated through the room 105 or chamber, with an incidental renewal of heat units and moisture therein, and to intermittently withdraw cool and foul or supersaturated gas and to replace it with a fresh supply of heated gas, all as determined 110 by temperature and humidity conditions within the room or chamber.

It is not my intention to limit the invention to the temperature, degree of humidity or the gas employed in the method or art, 115 nor to the details of construction of the apparatus shown in the drawings, it being apparent that all such details may be varied without departing from the spirit and scope of the invention.

While I have referred herein to "saturated air", this term is used to indicate the degree of saturation herein referred to as being suitable for the purposes of the invention.

Having described the invention what I claim as new and desire to have protected by Letters Patent is:

1. That process of drying rubber which consists in maintaining its surface moist 120

while subjecting it to the action of segregated volumes of heated and humidified gas in circulation which volumes are successively removed when excessively humid and 5 replaced by freshly conditioned volumes of gas until the rubber reaches a substantially uniform and nearly dry condition.

2. The herein described method of treating rubber consisting in charging a room or 10 chamber containing the rubber to be treated with gas, at a suitable temperature and degree of saturation, repeatedly circulating the gas with which the room or chamber is charged through said room or chamber, 15 reheating and humidifying the gas while it is being so circulated, and intermittently interrupting the circulation of said gas by withdrawing the cooled and supersaturated or fouled gas from the room or chamber 20 and replacing it with fresh conditioned gas.

3. A process of treating rubber which consists in abstracting moisture therefrom by a segregated volume of circulating heated and humidified gas until the moisture 25 content thereof approximates a predetermined limit, removing and replacing the gas thus fouled by a fresh volume of heated gas having a lower humidity than that of the discharged foul gas.

30 4. A process of drying rubber including subjection of the rubber to a segregated volume of circulating gas at approximately a predetermined temperature and humidity and until the humidity increases to a predetermined extent, removing the thus fouled 35 gas and replacing it with a fresh supply of gas having a lower degree of saturation than the foul gas removed.

5. A process of drying rubber which consists in charging a container for the rubber with a volume of humidified and heated gas, circulating the gas by withdrawing and reintroducing it into the chamber until its 40 humidity reaches a predetermined limit, discharging the gas thus fouled by the fresh volume of heated gas having a lower humidity, and circulating the freshly introduced gas as before, and repeating the above steps until the rubber is sufficiently dry.

50 6. Apparatus for treating rubber comprising a chamber adapted to contain rubber to be treated, a humidifying device and a source of gas supply communicating therewith, a conduit leading from the humidifying device to said chamber, a duct adapted to return the treated gas from the chamber to said humidifying device, and means automatically controlled by the degree of saturation of said gas in the chamber for regulating the flow of gas from the source of supply and the action of the humidifying device.

7. Apparatus for treating rubber comprising a room adapted to contain rubber to be treated, a humidifying device communicating with a source of gas supply, a

conduit leading from said humidifying device to the chamber, a valve intermediate the chamber and the atmosphere, a duct adapted to return the treated gas from said chamber to the humidifying device, and means automatically controlled by a condition of the gas in said chamber for shutting off said duct from the humidifying device and opening the said valve.

8. In an apparatus for treating rubber, 75 a chamber adapted to contain rubber to be treated, a humidifying device, a gas supply, a valve between the humidifying device and gas supply, a conduit leading from the humidifying device to the chamber, a duct 80 for returning treated gas from the chamber to the humidifying device, and means controlled by a condition of the gas in said chamber for shutting off said duct from the humidifying device and opening the said 85 valve.

9. An apparatus for treating rubber embodying therein a room or chamber adapted to contain rubber to be treated, a heater, a conduit communicating with a source of 90 gas supply and said heater, means injecting steam into the gas while it is passing to said heater, means delivering the gas and steam after leaving said heater to said room or chamber, an off-take duct communicating with said room or chamber, and said heater, a purge duct opening within and discharging without said room or chamber, and valves in said first named conduit, said off-take duct and said purge duct whereby 95 a closed circulation of gas may be maintained, and a fresh supply of gas may be delivered to said room or chamber and a portion of the gas in said room may be simultaneously discharged through said 100 purge conduit.

10. An apparatus for treating rubber embodying therein a room or chamber adapted to contain rubber to be treated, a heater, a conduit communicating with a source of gas 110 supply and said heater, means injecting steam into the gas while it is passing to said heater, means delivering the gas and steam after leaving said heater to said room or chamber, an off-take duct having a plurality 115 of intake openings arranged about said room or chamber, and communicating with said room or chamber and said heater, a purge duct opening within and discharging without said room or chamber, and valves in 120 said first named conduit, said off-take duct and said purge duct whereby a closed circulation of gas may be maintained, and a fresh supply of gas may be delivered to said room or chamber and a portion of the gas in said 125 room may be simultaneously discharged through said purge conduit.

11. An apparatus for treating rubber embodying therein a room or chamber adapted to contain rubber to be treated, a heater, a 130

- conduit communicating with a source of gas supply and said heater, means injecting steam into the gas while it is passing to said heater, a valve mechanism whereby the volume of steam may be controlled, means delivering the gas and steam after leaving said heater to said room or chamber, an off-take duct communicating with said room or chamber and said heater, a purge duct opening within and discharging without said room or chamber, and valves in said first named conduit, said off-take duct and said purge duct whereby a closed circulation of gas may be maintained, and a fresh supply of gas may be delivered to said room or chamber and a portion of the gas in said room may be simultaneously discharged through said purge conduit.
12. An apparatus for treating rubber embodying therein a room or chamber adapted to contain rubber to be treated, a heater, a conduit communicating with a source of gas supply and said heater, means injecting steam into the gas while it is passing to said heater, means delivering the gas and steam after leaving said heater to said room or chamber, an off-take duct communicating with said room or chamber and said heater, a purge duct having a plurality of branches opening into the room or chamber on different levels, said duct discharging without said room or chamber and valves in first named conduit, said off-take duct and said purge duct whereby a closed circulation of gas may be maintained, and a fresh supply of gas may be delivered to said room or chamber and a portion of the gas in said room may be simultaneously discharged through said purge conduit.
13. An apparatus for treating rubber embodying therein a room or chamber adapted to contain rubber to be treated, a heater, a conduit communicating with a source of gas supply and said heater, means injecting steam into the gas while it is passing to said heater, means delivering the gas and steam after leaving said heater to said room or chamber, an off-take duct communicating with said room or chamber and said heater, a purge duct opening within and discharging without said room or chamber, valves in said first named conduit, said off-take duct and said purge duct, an hygrometer within said room or chamber, means whereby the valve in said off-take duct may be opened or closed and the valves in said conduit and said purge duct may be closed or opened, simultaneously with the opening or closing of said valve in said off-take duct whereby a closed circulation of gas may be maintained, and a fresh supply of gas may be delivered to said room or chamber and a portion of the gas in said room may be simultaneously discharged through said purge conduit, and controlling means adapted to be actuated by said hygrometer whereby said valves will be automatically actuated.
14. An apparatus for treating rubber embodying therein a room or chamber adapted to contain rubber to be treated, a heater, a conduit communicating with a source of gas supply and said heater, means injecting steam into the gas while it is passing to said heater, a valve mechanism whereby the volume of steam may be controlled, means delivering the gas and steam after leaving said heater to said room or chamber, an off-take duct communicating with said room or chamber and said heater, a purge duct opening within and discharging without said room or chamber, valves in said first named conduit, said off-take duct and said purge duct, an hygrometer within said room or chamber, means whereby the valve in said off-take duct may be opened or closed and the valves in said conduit and said purge duct may be closed or opened, simultaneously with the opening or closing of said valve in said off-take duct whereby a closed circulation of gas may be maintained, and a fresh supply of gas may be delivered to said room or chamber and a portion of the gas in said room may be simultaneously discharged through said purge conduit, and controlling means adapted to be actuated by said hygrometer whereby said valves will be automatically actuated.
15. An apparatus for treating rubber embodying therein a room or chamber adapted to contain rubber to be treated, a heater, a conduit communicating with a source of gas supply and said heater, means injecting steam into the gas while it is passing to said heater, means delivering the gas and steam after leaving said heater to said room or chamber, an off-take duct communicating with said room or chamber and said heater, a purge duct opening within and discharging without said room or chamber, valves in said first named conduit, said off-take duct and said purge duct, a valve mechanism whereby the volume of steam may be controlled, an hygrometer within said room or chamber, means whereby the valve in said off-take duct may be opened or closed and the valves in said conduit and said purge duct may be closed or opened, simultaneously with the opening or closing of said valve in said off-take duct whereby a closed circulation of gas may be maintained, and a fresh supply of gas may be delivered to said room or chamber and a portion of the gas in said room may be simultaneously discharged through said purge conduit, and controlling means adapted to be actuated by said hygrometer whereby said valves will be automatically actuated.
16. An apparatus for treating rubber em-

- bodying therein a room or chamber adapted to contain rubber to be treated, a heater, a conduit communicating with a source of gas supply and said heater, means injecting steam into the gas while it is passing to said heater, means delivering the gas and steam after leaving said heater to said room or chamber, an off-take duct communicating with said room or chamber and said heater, a purge duct opening within and discharging without said room or chamber, valves in said first named conduit, said off-take duct and said purge duct, a valve mechanism whereby the volume of steam may be controlled, an hygrometer within said room or chamber, means whereby the valve in said off-take duct may be opened or closed and the valves in said conduit and said purge duct may be closed or opened simultaneously with the opening or closing of said valve in said off-take duct whereby a closed circulation of gas may be maintained, and a fresh supply of gas may be delivered to said room or chamber and a portion of the gas in said room may be simultaneously discharged through said purge conduit, controlling means adapted to be actuated by said hygrometer whereby said valves and said valve mechanism will be automatically actuated, a thermostat within said room or chamber and means adapted to be actuated by said thermostat, whereby the temperature of said heater may be automatically controlled.
17. An apparatus for drying materials including a chamber, means for intermittently circulating gas through the chamber until saturated to a predetermined extent,
- means for supplying fresh gas intermittently to the chamber and for exhausting gas intermittently from the chamber, and means controlled by the conditions within the chamber for governing alternative operation of the first two means mentioned and maintaining the humidity and temperature of the gas contained in the chamber within predetermined limits.
18. An apparatus for treating rubber including a chamber, means within the chamber sensitive to the humidity and temperature of the atmosphere therewithin, means controlled by the first mentioned means for introducing a volume of fresh gas within the chamber at a substantially definite degree of humidity and heat, means for exhausting overly moist gas from within the chamber, and means for intermittently circulating an introduced segregated volume of the gas until its humidity reaches a predetermined limit.
19. An apparatus for heating rubber including a chamber, a supply duct, a return duct, an exhaust duct, communicating vents between the several ducts and the chamber, a heater, a humidifier, valves for governing the admission exhaust and circulation of said gas to from and through said chamber, a gas moving device, and means within the chamber for governing the operation of said valves to control the movement of the gas while maintaining it at a substantially uniform humidity and temperature.

Signed at Detroit, Michigan, this 29 day of September 1917.

ERNEST A. WULLENWEBER.
